United States Patent Office

Des. 209,138
Patented Nov. 7, 1967

209,138

COMBINED TRACTOR BODY AND FRAME

William H. Armstrong and Jack L. Ponkey, Bloomfield Hills, Mich., assignors to Gilson Bros. Co., Plymouth, Wis., a corporation of Wisconsin

Filed Feb. 17, 1967, Ser. No. 5,845

Term of patent 14 years

(Cl. D14—3)

FIG. 1 is a front three-quarter perspective view of a combined tractor body and frame embodying the present invention.

FIG. 2 is a front view thereof.

FIG. 3 is a rear three-quarter perspective view thereof.

FIG. 4 is a plan view thereof.

FIG. 5 is a plan view of the frame.

FIG. 6 is a side view of the frame.

The broken line showing is for illustrative purposes only.

We claim:

The ornamental design for a combined tractor body and frame, as shown and described.
